UNITED STATES PATENT OFFICE.

FRANK HEDLEY, OF YONKERS, AND JAMES S. DOYLE, OF MOUNT VERNON, NEW YORK.

FARE BOX.

Application filed January 11, 1921. Serial No. 436,430.

This invention relates to fare boxes or receptacles.

The object of the invention is to provide a structure of fare box or receptacle which is simple, composed of few parts, is strong and durable, and efficient in use.

A further object of the invention is to provide a fare box structure, in the use of which a coin or token is employed to complete electric connection between contacts contained in an electric circuit, and wherein the operation and functioning of each fare or token deposited is not interfered with by a subsequently or successively introduced fare or token.

Other objects of the invention will appear more fully hereinafter.

The invention consists substantially in the construction, combination, location and relative arrangements of parts, all as will be more fully hereinafter set forth, as shown in the accompanying drawings and finally pointed out in the appended claims.

Referring to the accompanying drawings: Figure 1 is a view in side elevation of a fare box or receptacle embodying the principles of our invention, the side plate of the casing or box being removed to disclose the structure of the interior mechanism.

Fig. 2 is a top plan view of the same, the top cover plate of the box or casing being removed.

Fig. 3 is a broken detail view in vertical section on the line 3—3, Fig. 2, looking in the direction of the arrows.

Fig. 4 is a similar view on the line 4—4, Fig. 2, looking in the direction of the arrows.

Fig. 5 is a view similar to Fig. 2, showing the coin or token lever in its displaced position for transfer of a coin or token into position to be delivered into the receptacle.

Fig. 6 is a broken detail view in section on the line 6—6, Fig. 5, looking in the direction of the arrows.

Fig. 7 is a broken detail view in horizontal section on the line 7—7, Fig. 6, looking in the direction of the arrows.

Fig. 8 is a view similar to Fig. 1, taken from the opposite side of the fare box, the side plate of the casing being removed.

The same part is designated by the same reference numerals wherever they occur throughout the several views.

In our applications for patents, Serial

Numbers 433,693 and 433,692 filed December 28, 1920, we have set forth, described and claimed various arrangements and systems for controlling restricted passageways, and wherein the deposit of coins or tokens effect control of certain circuits employed in said systems. The present invention relates more particularly to a structure of fare box suitable for use in connection with such control arrangements or systems. While, however, our present invention is particularly well adapted for use in connection with such systems, it is equally effective for use in other relations and other systems of fare or token collection.

In the practical use of fare collection devices in connection with the operation of street cars, subway and elevated trains, ferries, amusement parks, theatres, moving picture establishments and the like, it is important to provide means whereby the operation and functioning dependent upon the deposit of each coin or token shall not be disturbed or interfered with by a deposit of a succeeding coin or token. It is also important to provide for the rejection and elimination of unauthorized or improper coins or tokens, or coins or tokens of improper size. It is also desirable to effect a suitable registration of each coin or token deposited. By reason of the work required to be accomplished by fare box structures in effecting the deposit and accurate registration of successively deposited coins or tokens, it is important that the fare box structure be not only free from complicated mechanism, but also that such mechanism be strong, sturdy and durable and capable of withstanding without danger of derangement the excessive duty imposed thereon.

It is among the special purposes of our present invention to provide a fare box structure which accomplishes these results and secures in a most simple and efficient manner the advantages suggested.

In accordance with our invention we employ a main supporting frame which in the form shown includes a vertically disposed plate 10, upon which the various working parts of the apparatus are supported. Upon this supporting frame is mounted a casing 11, containing the register mechanism, which may be of any suitable form of odometer or counter mechanism, such as is ordinarily employed in fare register de-

2 vices, including an operating spindle 12, which extends through the casing 11. The register mechanism may also include the usual reset rod 13, for the register mechanism, provided with the usual reset grip 14, and locking spring 15. These parts, however, in the specific details thereof, form no part of our present invention. The spindle 12 of the register mechanism may be 10 actuated, and the coin or token controlled in its actuation in any suitable or convenient manner. A simple arrangement is shown which we have found effective, consisting of a magnet coil 16, see Fig. 8, 15 which is supported within a frame 17, suitably mounted and supported upon the main frame member 10. The stem portion of the magnet coil armature carries a yoke 18, which is pivotally and loosely connected 20 to the slotted end of a clamp arm 19, which is clamped on one of the projecting ends of the register spindle 12, whereby whenever the magnet coil 16 is energized, the magnet coil armature is shifted upwardly, 25 in the arrangement shown in Fig. 8, whereby said spindle 12 is rocked in one direction, and when said magnet coil is de-energized, said armature descends whereby said spindle 12 is rocked in the other direction. A clamp arm 20 is mounted upon the 30 other end of the register spindle 12. This clamp arm is normally held in an initial or retracted position whenever the circuit of magnet coil 16 is open. When, however, the circuit of said magnet coil is 35 closed, and the register spindle 12 is rocked, the clamp arm 20 is also rocked, and in its rocking movement it engages an inclined or cam surface 21, on the tail end of the 40 coin lever 22. This lever 22 is pivotally mounted upon a vertical stud 23, to rock or swing horizontally. The stud 23 is carried in a post 24, suitably mounted upon a frame member or plate 25. A spring 45 23 connected at one end to the coin lever at its other end, as at 27, adjustably connected to a bracket 28 on the frame plate 25, serves to maintain the cam surface 21 of the coin lever in bearing relation with 50 respect to the end of the clamp arm 20, and to return or restore the coin lever 22 to its initial position after having been displaced therefrom through the rocking movement of clamp arm 20, when the latter returns 55 to its initial position, that is, when the magnet coil 16 becomes deenergized. The opposite end of the coin lever oscillates back and forth between the arms of a bracket 30, suitably supported upon the 60 frame plate 25, and if desired, an adjustable stop 31 may be mounted in one of the arms of the yoke to adjustably limit and regulate the extent of oscillating movement of the coin lever when displaced by the 65 operation of the clamp arm 20.

The normal position of the coin lever is indicated in Figs. 2 and 3, and when in its initial position a vertical slot 32 there-through is brought into register relation with respect to a corresponding slot 33 70 formed in a mouth-piece 34, which is mounted upon the top or cover plate 35 of the casing. The dimensions of the slots 33, 32, should be such as to receive there-through coins or tokens of the required 75 size. This will eliminate the possibility of coins or tokens of over size being employed, and in case coins or tokens of less than the prescribed or predetermined size are inserted through the slot 33 of the mouth-piece 34, such under-size coins or tokens will drop on through the slot 32 in the coin lever, and will fall into a return chute 36, from which they may be removed through 80 an opening 37 in the side wall or plate 38 of the casing. If, however, the proper predetermined size of coin or token is deposited through the mouth-piece 34, it is received in the slot 32 of the coin lever, 85 and will engage between suitable conducting or terminal blocks 39, 40, which are disposed immediately beneath the horizontal plane of operation of the coin lever, see Fig. 4, and are mounted upon the frame member 25. The coin indicated at 41 is, however, retained between the walls of the slot 32 in the coin lever while at the same time bridging the space between the terminals 39, 40. In the case where the circuit of the 90 magnet coil 16 is coin or token controlled, the terminals 39, 40, are arranged in the circuit of said magnet coil, so that when a coin or token bridges the space between the terminals 39, 40, the circuit of said magnet coil is completed, and said 95 magnet is energized. This effects an actuation of the counter or register spindle 12, and consequently also a lateral displacement of the coin lever through the engagement of the clamp arm 20 with the inclined or cam surface 21 of said coin lever, and consequently said lever is rocked upon its pivot stud 23, so as to carry the lever 22 into the position thereof shown in Figs. 4, 5 and 6. When in this position, the 100 coin slot 32 of the coin lever is brought into register with a chute 42, into which the coin drops by gravity, and which constitutes the receiving receptacle for the proper coins deposited. This lateral rocking movement of the coin lever with the coin retained between the walls of the slot 32, carries the coin from between the terminal blocks 39, 40, thereby permitting the coin to be released and to fall into the receiving chute 105 42. Adjacent the slot 32 of the coin lever is an extension surface 43, which, when the lever is rocked into position for the coin or token carried thereby to fall into the receiving chute 42, is brought beneath 110 115 120 125 130

the slot 33 and the mouth-piece 34, and constitutes a ledge or support for the next succeeding coin or token which may be inserted into the slot 33 while the lever is in its

displaced position, and hence such subsequently deposited coin is retained in a position where it cannot interfere with or interrupt the operations or functioning resulting from the deposit of the previous 10 coin or token. The subsequently introduced coin is retained in its position supported upon the ledge 43 until the coin lever returns to its initial position, whereupon the second coin drops into the coin slot 32 in the lever 22, and the cycle of operation above described is repeated.

The terminal blocks 39, 40, may be mounted in any suitable or convenient manner. The block 39 is fastened to the frame member 25, and constitutes a ground connection through the framework of the fare box for the circuit which is closed through a coin or token between the blocks 39, 40.

The terminal block 40 is insulated from the frame member 25, and a circuit terminal of the magnet coil is connected to the terminal block 40, as indicated at 44. In the arrangement shown the block 40 is fastened to the insulating member 45, which is bolted or otherwise suitably secured to the frame member 25 with an insulating strip 46 interposed therebetween.

The structure above described may be enclosed within any suitable arrangement of casing. We have shown a casing which includes the side plates 38, 47 and 48, and the cover plate 35. If desired, one of the side walls 49 of the casing may form a hinged door.

From the foregoing description it will be seen that we provide an exceedingly simple, rugged and efficient structure of fare box mechanism, having few parts that are liable to get out of order by continued use of the apparatus, and wherein provision is made for rejecting coins or tokens of undesirable size, and where the functioning and operation resulting from the insertion of a coin or token of proper size is not interfered with or disturbed by too rapid successive insertions or deposits of coins or tokens, it being necessary for the coin operating lever, after being displaced from its normal retracted coin or token receiving position, to be returned to its initial receiving position before another coin or token can be properly inserted.

When the magnet coil 16 is energized, it operates circuit control or bridging members 50 for proper co-operation with circuit terminals 60.

It will be understood that many variations and changes in the details of the structure and arrangement might readily occur to persons skilled in the art and still

fall within the spirit and scope of our invention. We do not desire, therefore, to be limited or restricted to the exact details shown and described.

But having now set forth the objects and nature of our invention, and a construction embodying the principles thereof, what we claim as new and useful and of our own invention and desire to secure by Letters Patent is:

1. A fare box structure having a coin or token receiving slot in combination with a displaceable lever having a co-operating coin or token receiving slot, a coin or token receiving chute arranged out of line with the fare box receiving slot, and electrically operated devices controlled by the deposit of a coin or token for shifting said lever from registering relation with respect to the fare box slot into registration with the receiving chute, the said lever having an extension or supporting surface adjacent its receiving slot to form a support for a coin inserted in the fare-box receiving slot when the slot in the lever is out of register with said receiving slot.

2. A fare box structure having a coin or token receiving slot in combination with a displaceable lever having a co-operating coin or token receiving slot, a coin or token receiving chute arranged out of line with the fare box receiving slot, means for shifting said lever from registering relation with respect to the fare box slot into registration with the receiving chute, the said lever having an extension or supporting surface adjacent its receiving slot to form a support for a coin inserted in the fare-box receiving slot when the slot in the lever is out of register with said receiving slot, and means controlled by the deposit of a coin or token for shifting said coin lever.

3. A fare box structure having a coin or token receiving slot in combination with a displaceable lever having a co-operating coin or token receiving slot, a coin or token receiving chute arranged out of line with the fare box receiving slot, means for shifting said lever from registering relation with respect to the fare box slot into registration with the receiving chute, the said lever having an extension or supporting surface adjacent its receiving slot to form a support for a coin inserted in the fare-box receiving slot when the slot in the lever is out of register with said receiving slot, and contact terminals arranged in line with the fare box and lever slots when said lever is in initial position, and adapted to be bridged by a coin deposited in said slots.

4. A fare box structure having a coin or token receiving slot in combination with a displaceable lever having a co-operating coin or token receiving slot, a coin or token receiving chute arranged out of line with

the fare box receiving slot, means for shifting said lever from registering relation with respect to the fare box slot into registration with the receiving chute, the said lever having an extension or supporting surface adjacent its receiving slot to form a support for a coin inserted in the fare-box receiving slot when the slot in the lever is out of register with said receiving slot, and contact terminals arranged in line with the fare box and lever slots when said lever is in initial position, and adapted to be bridged by a coin deposited in said slots, the walls of the slot in the lever retaining engagement with the deposited coin while the latter is in bridging relation with respect to said terminals.

5. A fare box structure having a coin or token receiving slot in combination with a pivotally mounted coin lever having a co-operative coin receiving slot, means for normally maintaining the slots of the box and lever in line with each other, a coin or token return chute arranged in line with said slots, a coin or token receiving chute arranged out of line with said slots, electrically operated devices controlled by the deposit of a coin or token for rocking said lever from its normal position into register alignment with the said coin receiving chute and means to retain a coin inserted in the fare-box receiving slot when said coin lever is displaced from initial position.

6. A fare box structure having a coin or token receiving slot in combination with a pivotally mounted coin lever having a co-operative coin receiving slot, means for normally maintaining the slots of the box and lever in line with each other, a coin or token return chute arranged in line with said slots, a coin or token receiving chute arranged out of line with said slots, and electrically operated devices controlled by the deposit of a coin or token for rocking said lever from its normal position into register alignment with the said coin receiving chute, said lever having a laterally extending supporting surface adjacent the slot therein to form a support for a coin inserted in the fare-box receiving slot when said lever is displaced from its initial position.

7. A fare box structure having a coin or token receiving slot in combination with a pivotally mounted coin lever having a co-operative coin receiving slot, means for normally maintaining the slots of the box and lever in line with each other, a coin or token return chute arranged in line with said slots, a coin or token receiving chute arranged out of line with said slots, means for shifting said lever from its normal position into register alignment with the said coin receiving chute, said means controlled by the deposit of a coin or token into the lever slot and means to retain a coin inserted in the

fare-box receiving slot when said lever is displaced from initial position.

8. A fare box structure having a coin or token receiving slot in combination with a pivotally mounted coin lever having a co-operative coin, receiving slot, means for normally maintaining the slots of the box and lever in line with each other, a coin or token return chute arranged in line with said slots, a coin or token receiving chute arranged out of line with said slots, means for shifting said lever from its normal position into register alignment with the said coin receiving chute, said means including a magnet coil and circuit terminals arranged in the circuit of said magnet coil, said terminals being bridged by the deposit of a coin or token into the slot in said lever and means to retain a coin inserted in the fare-box receiving slot when said coin lever is displaced from its normal position.

9. A fare box structure having a coin or token receiving slot in combination with a pivotally mounted coin lever having a co-operative coin receiving slot and a cam surface, means for normally maintaining the slots of the box and lever in line with each other, a coin or token return chute arranged in line with said slots, a coin or token receiving chute arranged out of line with said slots, and means for shifting said lever from its normal position into register alignment with the said coin receiving chute, said means including a rocking arm arranged to engage the cam surface on said lever.

10. A fare box structure having a coin or token receiving slot in combination with a pivotally mounted coin lever having a co-operative coin receiving slot and a cam surface, means for normally maintaining the slots of the box and lever in line with each other, a coin or token return chute arranged in line with said slots, a coin or token receiving chute arranged out of line with said slots, and means for shifting said lever from its normal position into register alignment with the said coin receiving chute, said means including a rocking arm arranged to engage the cam surface on said lever, and a spring normally acting to retain said lever in its initial position.

11. A fare box structure having a coin or token receiving slot in combination with a pivotally mounted coin lever having a co-operative coin receiving slot and a cam surface, means for normally maintaining the slots of the box and lever in line with each other, a coin or token return chute arranged in line with said slots, a coin or token receiving chute arranged out of line with said slots, and means for shifting said lever from its normal position into register alignment with the said coin receiving chute, said means including a rocking arm arranged to

engage the cam surface on said lever, a magnet coil for actuating said arm, the circuit of said magnet coil being controlled by a coin deposited in the slot in said lever.

12. A fare-box structure having a coin or token receiving slot in combination with a coin lever, having a co-operating slot, and normally held in line with the fare box slot, a coin receiving chute arranged out of line with the fare box slot, a register mechanism including a spindle, a magnet coil for actuating said spindle, an arm carried by said spindle, and engaging said coin lever to displace the same from register relation with the fare box slot into register relation with the coin chute.

13. A fare-box structure having a coin or token receiving slot, in combination with a coin lever, having a co-operating slot, and normally held in line with the fare box slot, a coin receiving chute arranged out of line with the fare box slot, a register mechanism including a spindle, a magnet coil for actuating said spindle, an arm carried by said spindle and engaging said coin lever to displace the same from register relation with the fare box slot into register relation with the coin chute, the circuit of said magnet coil being controlled by the deposit of a coin into a slot in said lever.

14. A fare-box structure having a coin or token receiving slot, in combination with a coin lever, having a co-operating slot, and normally held in line with the fare box slot, a coin receiving chute arranged out of line with the fare box slot, a register mechanism including a spindle, a magnet coil for actuating said spindle, an arm carried by said spindle and engaging said coin lever to displace the same from register relation with the fare box slot into register relation with the coin chute, the circuit of said coil including terminal blocks spaced apart from each other and adapted to be bridged by a coin carried in the slot of said lever.

15. A fare box having a coin or token receiving slot in combination with a coin lever pivotally mounted intermediate its ends, one

end of said lever having a coin receiving slot, the other end of said lever having a cam surface, means for normally retaining said lever in position for its coin or token receiving slot to register with the fare box slot, an arm engaging said cam surface, means for actuating said arm to rock said lever to carry the coin or token receiving slot in said lever out of register with the fare box slot, and into register with a coin receiving chute.

16. A fare box having a coin or token receiving slot in combination with a coin lever pivotally mounted intermediate its ends, one end of said lever having a coin receiving slot, the other end of said lever having a cam surface, means for normally retaining said lever in position for its coin or token receiving slot to register with the fare box slot, an arm engaging said cam surface, means for actuating said arm to rock said lever to carry the coin or token receiving slot in said lever out of register with the fare box slot, and into register with a coin receiving chute, and an adjustable stop to limit the rocking movement of said lever.

17. A fare box having a coin or token receiving slot in combination with a coin lever pivotally mounted intermediate its ends, one end of said lever having a coin receiving slot, the other end of said lever having a cam surface, means for normally retaining said lever in position for its coin or token receiving slot to register with the fare box slot, an arm engaging said cam surface, means for actuating said arm to rock said lever to carry the coin or token receiving slot in said lever out of register with the fare box slot, and into register with a coin receiving chute, and a supporting ledge or surface on said lever, arranged to form a support for a coin inserted in the fare-box receiving slot when the slot in the lever is out of register with said receiving slot.

In testimony whereof we have hereunto set our hands on this 31st day of December A. D., 1920.

JAMES S. DOYLE.
FRANK HEDLEY.
